UNITED STATES PATENT OFFICE

155,034

DESIGN FOR A VEHICLE HOOD ORNAMENT OR SIMILAR ARTICLE

Alvin W. Prance, Huntington Woods, Mich., assignor to Packard Motor Car Company, Detroit, Mich., a corporation of Michigan

Application November 4, 1947, Serial No. 142,303

Term of patent 3½ years

(Cl. D14—18)

To all whom it may concern:

Be it known that I, Alvin W. Prance, a citizen of the United States, residing at Huntington Woods, State of Michigan, have invented a new, original, and ornamental Design for a Vehicle Hood Ornament or Similar Article, of which the following is a specification, reference being had to the accompanying drawing, forming a part thereof.

Fig. 1 is a side elevational view of a vehicle hood ornament embodying my invention.

Fig. 2 is a plan view of the ornament.

Fig. 3 is a front elevational view of the ornament.

Figs. 4 and 5 are sectional views taken substantially on the lines 4—4 and 5—5 of Fig. 1 looking in the direction of the arrows.

Fig. 6 is a sectional view taken substantially on the line 6—6 of Fig. 2 looking in the direction of the arrows.

I claim:

The ornamental design for a vehicle hood ornament or similar article, substantially as shown.

ALVIN W. PRANCE.
